(57) **CLAIM**

An ornamental design for a cutting board, as shown and described.

DESCRIPTION

FIG. 1 is a perspective view of a cutting board according to my new design;

FIG. 2 is a top view thereof;

FIG. 3 is a cross-sectional view thereof, taken along line 3-3 of FIG. 2; and,

FIG. 4 is a cross-sectional view thereof, taken along line 4-4 of FIG. 2.

The broken lines represent environmental elements and form no part of the claimed design. The height-to-width-to-depth ratios of the cutting board may vary from the ratios of the specific embodiments shown in the Figures without departing from the claimed design.
